UNITED STATES PATENT OFFICE.

JOHN E. DENHAM, OF STANBERRY, MISSOURI.

SHEARING AND PUNCHING MACHINE.

SPECIFICATION forming part of Letters Patent No. 606,194, dated June 28, 1898.

Application filed June 11, 1897. Serial No. 640,360. (No model.)

To all whom it may concern:

Be it known that I, JOHN E. DENHAM, a citizen of the United States, residing at Stanberry, in the county of Gentry and State of Missouri, have invented a new and useful Shearing and Punching Machine, of which the following is a specification.

My invention relates to shearing and punching machines, and has for its object to provide a simple and compact construction and arrangement of parts whereby the operations of shearing metal rods and plates and punching, either by means of single or cluster punches, may be accomplished with facility.

Further objects and advantages of this invention will appear in the following description, and the novel features thereof will be particularly pointed out in the appended claims.

In the drawings, Figure 1 is a perspective view of a machine of the class mentioned constructed in accordance with my invention. Fig. 2 is a side view showing the opposite side of the machine. Fig. 3 is a detail view of the cluster-punch-operating devices, showing the swinging or movable bar elevated. Fig. 4 is a detail view in perspective of the punch-driving head detached. Fig. 5 is a detail transverse section of the pivotal guide-bearing in the plane of the securing-pin.

Similar numerals of reference indicate corresponding parts in all the figures of the drawings.

Supported by standards 1 and 2 are horizontal stationary bars 3 and 4, of which the upper bar 3 carries stationary shear-blades 5 and 6 to coöperate with corresponding movable shear-blades 7 and 8 on the swinging or movable bar 9. This movable bar is fulcrumed in a vertical slot in the rear standard 2 and operates at its free end in a corresponding slot in the front standard 1, the free end of the long arm of said bar 9 being constructed to form a rack 10, with which coöperates a gear 11. An operating-handle 12 is used in connection with the spindle 13 of this pinion for communicating rotary motion thereto in either direction to oscillate the swinging arm 9. Also in connection with the rear shear-blades 6 and 8 I preferably use a swinging guard 14, which is provided with an upwardly-

extending spindle 15, mounted in suitable bearings on the rear standard 2.

A series of cluster-punches 16 is supported by the stationary bar 3, the same being mounted in suitable aligned upper and lower guides 17 and 18 and being adapted to coöperate with a die-plate 19, supported by a seat 20 on the lower stationary bar 4, said die-plate being held in place by a suitable fastening device 21. These punches are designed to be operated separately by means of a punch-driving head or block 22, which is mounted to slide upon the swinging bar 9 for successive alinement with the punches. In the construction illustrated this driving-head is cut away at its center to receive the lower edge of the swinging bar 9 and is provided with inturned guide lips or ears 23 to fit in grooves 24, formed in the opposite side surfaces of the bar, and one groove is preferably provided at one end with a communicating outlet-opening 25, by which the head may be dismounted. Furthermore, it is desirable at each upward movement of the swinging or operating bar 9 to draw the punches, and hence I provide a lifting-arm 26, fulcrumed at 27 and extending under a suitable ear 28 on each punch, with its free end fitted in a suitable guide or keeper 29, and a trip 30, pivotally mounted upon the swinging or operating bar 9 and provided with a shouldered lower extremity to engage the free end of the lifting-bar when advanced into operative relation therewith by means of an inclined guide 31. The trip is preferably provided upon the side contiguous to the guide 31 with a pressure-spring 32, and the opposite side of the trip is provided with a cam-face 33 to engage a deflecting-stop 34, consisting in the present construction of an antifriction-roll, whereby the lower or free end of the trip is deflected forwardly to disengage its shoulder or notch from the free end of the lifting-bar and thereby release the latter. By this construction the punches are simultaneously drawn from the work when the upward movement of the operating-bar commences, but are immediately released when raised to the proper point to provide for the subsequent depression of either punch by means of the driving-head 22.

In addition to the cluster-punches I employ a single punch preferably arranged in rear of the standard 2 and carried by the short arm of the operating-lever 9. In the construction 5 illustrated this lever is provided with a socket 35, in which is fitted the head 36 of the single punch, said head being held in place by a latch or similar securing device 37, and the shank of the punch operates in a pivotally-mounted guide 38, of tubular construction, provided with a stem 39, which is mounted in a tubular bearing 40, and this tubular bearing is secured above the plane of the bar 3, between the walls of the slot in the rearstandard 2, by means of a bolt 41. The die 42 for 10 cooperation with the punch is carried by a fixed arm 43.

Furthermore, in order to facilitate the shearing of round rods I provide rod-shearing 20 devices consisting of openings 44, of different diameters, in the swinging or operating lever 9, preferably contiguous to and on either side of its fulcrum, and corresponding openings 45, formed in extensions or ears of the 25 upright 2 at one side of the plane of the operating-lever. When the operating-lever is elevated, these rod-shearing openings are brought into registration for the insertion of a rod, after which the movement of the lever 30 downwardly at its free end will produce the desired shearing action between the lever and the fixed openings in the standard.

Furthermore, in addition to the shearing and 35 punching devices above described I employ a tire-shrinker consisting of coöperating fixed and movable clutches, the movable clutch being carried by a swinging arm 46, mounted on the operating-lever 9, and consisting of fixed and swinging clutch members 47 and 48, the 40 latter of which is mounted upon a stud 49 on said swinging arm, and the fixed clutch consisting of a stationary jaw or member 50 and a movable jaw or member 51, the latter being fulcrumed upon a swinging arm 52. Said arm 45 52 is provided at its lower end with a pivot-pin 53, which forms a fulcrum for the movable member of the fixed clutch, while to the upper end of said swinging arm 52 is connected the actuating-lever 54. The connection 50 between the actuating-lever and the arm 52 is pivotal, as shown at 55, and this actuating-lever is connected by links 56 with an extension 57 of the swinging member 48 of the movable clutch. It will be seen that the 55 movement of the actuating-lever in the direction of the arrows in Figs. 1 and 2 will cause the movable clutch to swing toward the fixed clutch and will cause the swinging member 48 of the movable clutch to bite the article 60 which is arranged between the jaws of said clutch, and at the same time the pressure applied to the upper extremity of the swinging arm 52, which carries the movable member of the fixed clutch, will force the movable member 51 of the fixed clutch into more intimate contact with the article engaged thereby.

From the above description it will be seen

that the construction and arrangement of the machine are simple and compact, bringing the various coöperating parts thereof within reach 70 of the operator, and that in particular the punching devices are so arranged as to receive efficient power in operation, while enabling the work to be adjusted accurately with relation thereto. 75

Various changes in the form, proportion, and the minor details of construction may be resorted to without departing from the spirit or sacrificing any of the advantages of this 80 invention.

Having described my invention, what I claim is—

1. In a machine of the class described, the combination with a plurality of punches arranged in series, of an operating-lever having a fixed pivot and arranged parallel with the series of punches, and a punch-driving head adjustably mounted upon the lever for movement independently of the same to arrange it in the plane of either of the punches, 90 substantially as specified.

2. In a machine of the class described, the combination of a plurality of punches arranged in series, an operating-lever arranged parallel with the series of punches and capable of swinging movement, and a punch-driving head mounted to slide upon the operating-lever for arrangement in the plane of either of the punches, said head having in-turned guide fingers or ears to engage grooves 100 in the opposite side surfaces of the operating-lever, substantially as specified.

3. In a machine of the class described, the combination with a series of punches, of an operating-lever provided with means for successively driving the punches, a lifting-arm arranged in operative relation with the punches and adapted when elevated at its free end to draw the latter, and a trip carried by the operating-lever for engaging and communicating upward movement to the free end of the lifting-arm, substantially as specified. 105

4. In a machine of the class described, the combination with a series of punches, of an operating-lever provided with means for successively driving the punches, a lifting-arm arranged in operative relation with the punches and adapted when elevated at its free end to draw the latter, a trip carried by the operating-lever for engaging and communicating upward movement to the free end of the lifting-arm, and means for disengaging the trip from the lifting-arm when it reaches a predetermined point, substantially as specified. 110

5. In a machine of the class described, the combination with a series of punches, of an operating-lever provided with means for successively driving the punches, a lifting-arm arranged in operative relation with the punches and adapted when elevated at its free end to draw the latter, a trip carried by the operating-lever for engaging and communicating upward movement to the free end of the lift- 115 120 125 130

ing-arm, and means, consisting of a cam, on the trip, and a fixed stop for coöperation therewith, to disengage the trip from the lifting-arm, substantially as specified.

5 6. In a machine of the class described, the combination of terminal standards connected by stationary upper and lower bars 3 and 4, a movable bar mounted to swing in the plane of the fixed bars, means for actuating said movable bar, shear-blades carried by the movable and upper fixed bars respectively contiguous to the standards, a series of punches mounted in guides located between the shear-blades on the upper fixed bar, a die-plate carried by the lower fixed bar, adjustable means carried by the swinging bar for successively driving the punches, a lifting-arm mounted for swinging movement upon the upper fixed bar for coöperation with projections on the punches, and trip devices actuated by the

swinging bar for operating the lifting-arm, substantially as specified.

7. In a machine of the class described, the combination with a fixed die, of an operating-lever provided with a socket, a punch 25 having a head removably fitted in said socket, an adjustable latch for locking the punch-head in its socket, and a pivotally-movable guide for the punch, the same consisting of a guide-tube having a stem, and a tubular bearing adapted to receive the stem, substantially as specified. 30

In testimony that I claim the foregoing as my own I have hereto affixed my signature in the presence of two witnesses.

JOHN E. DENHAM.
